United States Patent Office.

JAMES E. HILLS, OF ORANGE, MASSACHUSETTS.

Letters Patent No. 90,945, dated June 8, 1869.

IMPROVEMENT IN KEY-FASTENER.

The Schedule referred to in these Letters Patent and making part of the same.

To all persons to whom these presents may come:

Be it known that I, JAMES E. HILLS, of Orange, of the county of Franklin, of the State of Massachusetts, have invented a new and useful Key-Fastener or safety-apparatus; and do hereby declare the same to be fully described in the following specification, and represented in the accompanying drawings, of which—

Figure 1 is a top view, and

Figure 2, a side elevation of it.

Figure 3 is a longitudinal section of the clamp-screw supporter or key-hole plate.

The purpose of the invention is to so fasten a key when in the lock of a door, that such key cannot be revolved by nippers applied to it from the outside of the door, the apparatus being intended as a means of safety or security, or as a preventive of the unlocking of the lock by a burglar.

It consists—

First, of a screw-nut, A, provided with two prongs or claws, *a a*, extended from it, and with an interval or space, *b*, between them, the whole being as represented.

Second, of a long screw, B, to screw directly or transversely through the clawed nut.

Third, of the screw-supporter C, which, as shown, consists of a plate provided with a concavo-convex projection, *b'*, or with such a hook, *e*, such hook and projection being arranged in manner as shown. The screw-supporter C and the duplex-clawed nut A, I usually connect by a chain, D.

To use the apparatus, the supporter C is to be hung by its hook upon the shank of a key when the latter may be in the key-hole and lock of a door. The projection *b'* is to extend into the key-hole or the key-

passage of the escutcheon-plate. Next the end or front of the screw B is to be inserted in the cavity or hollow *d* of the projection *b*, and the clawed nut is to be brought up to the shank of the key, so that such shank may be directly between the two claws. Next, the screw should be revolved so as to advance the claws tightly upon the handle of the key, and cause it to be held firmly between them and that surface of the nut over which they project.

The key will thus be held so that it cannot be easily revolved by nippers applied to it at the end of the shank.

The projection *b* aids in keeping the supporter C in place over the key-hole, especially should the supporter be unprovided with the hook to sustain it in the key. The projection also prevents the supporter from being slipped laterally across the key-hole. The cavity in the plate or projection serves to hold and support the end of the screw.

The whole apparatus is one of special advantage to a traveller, as it becomes a means of safety, enabling him to effectually secure a key in the lock of an apartment into which he may have retired for rest, or otherwise.

I claim the combination of the screw B, the duplex-clawed nut A, and the screw-supporter C, the whole to be employed with a key in manner and for the purpose as set forth.

I also claim the screw-supporter, as made with the hook and the concavo-convex projection, as specified.

JAMES E. HILLS.
